ADJUSTABLE CANDLESTICK

Emil Ager-Wick, Arendal, Norway

Application March 10, 1937, Serial No. 129,998
In Norway November 18, 1936

1 Claim. (Cl. 67—23)

My invention relates to an improvement in candle sticks providing self-centering means adjustable to hold any size candle with a tight grip and in a perfectly perpendicular position. 5 The objects of my invention are: To provide an adjustable receptacle for the end of the candle suitable to hold any size candle with a tight grip, to provide means for automatically centering the candle in the candle holder to prevent 10 dripping by holding the candle perfectly perpendicular, to provide such self-centering and gripping means which will not in any way detract from the artistic appearance of the candle stick, and to provide such adjustable means 15 at a minimum cost. Other objects of this invention will be apparent during the course of the following description.

In the accompanying drawing, forming part of this specification, and in which like numerals are employed to designate like parts throughout the same,

Figure 1 is a side elevation of a candle stick embodying my invention,

Figure 2 is a top view of the assembled candle receptacle,

Figure 3 is a partial section of the candle receptacle along the line 3—3 in Fig. 1,

Figure 4 is a section along line 4—4 in Fig. 3,

Figure 5 is a plan view of one of the receptacle 30 jaws, and, Figure 6 is a section along the line 6—6 in Fig. 3.

In the drawing, where for the purpose of illustration, is shown a preferred embodiment of my invention, the numeral 10 designates the base 35 of the candle stick which may be of any conventional design. The candle receptacle 11 has a downwardly narrowing, conical shape and the top of same is covered by the cap 12 which has a central opening upward, as shown in Fig. 2. The upper end of the conical candle receptacle 40 has a flange 14 fitting into the cap 12, the lower edge 15 of the cap 12 being spun over the flange 14, but free to turn on same, as indicated in section in Fig. 3. Between the flange 14 and 45 the cap 12 are placed three segments or jaws 13 of shape as shown in Fig. 5. These segments 13 have each two projections, one 16 turned perpendicular to the plane of 13 in one direction, and one 17 turned perpendicular to 13 in the opposite direction. Inside and directly under the cap 12 is fastened a washer 18 having three slots 19, see Fig. 4, and similar slots 20 are cut in the flange 14 as shown in Fig. 6.

The three segments, or jaws, 13 are placed 50 between the washer 18 and the flange 14 in a manner so that the projections 16 and 17 are

engaged in the slots 19 and 20 in, respectively, the washer 18 and the flange 14. A slight turn of the cap 12 thus will give the ends of the segments 13 which are held in slots 19 a circular motion. These segments however are held at the other end in slots 20, and a slight turn of the cap 12 will therefore cause a uniform motion of all three segments toward or away from the central axis of the candle stick, as indicated in Fig. 2. 10

The operation of my invention is as follows: The three segments 13 act similarly to the jaws in a universal chuck. Due to the fact that all three segments are identical, and make identical motions for a given angular displacement of the cap 12, the inside edges of these segments 13 will always remain equidistant from the central axis of the candle receptacle. A body, such as a candle, when placed between the jaws 13 may be held tight by turning the cap 12 until the jaws touch or dig into the sides of the candle. The conical shape of the receptacle 11 will furthermore automatically centre the lower end of the candle and thus insure that the same will be held in a perfectly perpendicular position. 20 The action of the chuck-jaws 13 may best be described as being similar to that of the iris diaphragm commonly used in cameras, although widely varying jaws may be used without departing from the scope of the present invention. 25

Having thus described my invention what I claim as new and wish to secure by Letters Patent of the United States is as follows:

In an adjustable candlestick the combination 35 of a conical base; a smaller conical shell fastened to the top of said conical base, and with its apex directed downwardly against the apex of the conical base; a flange surrounding the top of said smaller conical shell; a circular washer with three small radially extending, rectangular slots 40 placed on top of said flange, and concentric with same; three thin segmentary washers, each with a bent-up tab at either end, placed on top of said circular washer and with said metal tabs of one end of said segmentary washers engaged 45 in said radially extending rectangular slots; a second circular washer identical with the first placed on top of said segmentary washers, and with the metal tabs of the other end of these segmentary washers engaged upwardly through 50 said radial rectangular slots of said second circular washer, and a top washer, cupped and spun over said other washers and attached to and turnable on said flange of said upwardly direct- 55 ed conical shell.

EMIL AGER-WICK.
